(57) **CLAIM**

The ornamental design for a throttle cruise control, as shown and described.

DESCRIPTION

FIG. 1 is a perspective view of a throttle cruise control showing my new design in use;

FIG. 2 is a front elevation as viewed in FIG. 6;

FIG. 3 is a right side elevation as viewed in FIG. 6;

FIG. 4 is a rear elevation as viewed in FIG. 6;

FIG. 5 is a left side elevation as viewed in FIG. 6;

FIG. 6 is a top view; and,

FIG. 7 is a bottom view.

The throttle grip and handle bar switch housing shown in broken lines in FIG. 1 and the lever shown in broken lines in FIGS. 1-7 denote the nature and environmental use of the design are not part of the design.
